CREATION OF MARBLEIZED PATTERNS
FROM SEMIFLUID SUBSTANCESConrad C. A. Reetz, Seattle, Wash., assignor of
one-half to Lawrence A. Bloom, Seattle, Wash.

Application November 21, 1944, Serial No. 564,535

5 Claims. (Cl. 18—48.8)

1

This invention relates to the art of mixing, particularly the art of mixing substances of a semifluid nature, and its general object is to devise a machine functional to harmoniously blend separate streams of differently colored matter and from such blending create a marbleized mass. More especially stated, it is the object of the invention to provide a machine operative to accomplish its said marbleizing function by converting each of the several streams of semifluid matter into multiple strips, maintaining individuality as between these strips throughout a period necessary to effect heterogeneous distribution, and thereafter interlacing these various strips into a commingled whole.

Further and still more particular objects and advantages are inherent to the invention and, with the foregoing, will appear and be understood in the course of the following description and claims, the invention consisting in the new process of marbleizing semifluid substances and in the novel construction, adaptation and combination of parts comprising the machine for practicing same, and as will be hereinafter described and claimed.

In the accompanying drawings:

Figures 1, 2 and 3 are views taken partly in section and partly in elevation—fragmentary as respects Figs. 1 and 3—to portray a machine having its parts arranged and constructed in accordance with the now preferred embodiment of the invention; and

Figs. 4, 5 and 6 are horizontal sections taken on the respective lines 4—4, 5—5, and 6—6 of Fig. 3.

It may be here pointed out that the invention relates especially to the marbleizing of ice cream, and for which there is a constant demand, but lends itself with equal efficiency to substantially any semifluid substance which, following working in a plastic state, will set and maintain such pattern as may be given thereto. The several compositions of matter having various formulas and which, by wide usage of the term, are now recognized under the generic head of "plastics" are a self-evident example.

In carrying the invention into practice, the machine which I provide is characterized by its employment of a severality of interfitting tubes, three being shown, and of these tubes one constitutes an outer casing member and is indicated in the drawing by the numeral 7, a second tube, denoted 8, is sleeved therein, and a third tube, designated 9, is in turn sleeved within the tube 8. The tubes are assembled from the head end by

2

slipping one within another and provide a ground-joint fit as between a tapering shoulder produced upon the underside of head prominences of the tubes 8 and 9 and mating seats therefor provided by the tubes 7 and 8, respectively. Clamping nuts 10 and 11 are suitably applied to the assembly. The relationship as between the tubes is such as will assure a relatively snug fit while admitting to a ready dismantling for purposes of cleaning.

First describing the outer tube which, as aforesaid, serves the office of a casing, the same is given a comparatively uniform diameter throughout the greater part of the length and at the bottom narrows down and terminates in a somewhat constricted discharge neck 12. Provided on this neck are external threads permitting of the joinder thereto of a discharge conduit (not shown) which, either directly or through branch lines, is arranged and adapted to carry the output of the machine to cups or other like receptacles acting as molds. Proximate to the casing's head end and located at equidistantly spaced intervals of the circumference are a plurality of branch inlets 13 (four by preference), and these inlet branches are suitably formed, as by external threads, for accommodating the detachable connection of feed lines (not shown) through which are supplied—under pressure—differently colored streams of the substance to be worked. In the instance of ice cream, a pressure of from 55 to 80 pounds has been found to be the most desirable, and with the cream being under a temperature condition approximating 24° F. The creams may be of a different color in the case of each separate line, or the diametrically opposite inlet branches may both handle a cream of the same color characteristic.

Received through the open mouth of this casing member 7, and arranged to find lodgment in the basal end thereof is a vaned structure presenting blades 14 radiating from a center-bored hub, and carried by this hub and projecting upwardly therefrom is a shaft 15. To lie in surmounting relation to the vanes, a pair of axially spaced screw-worms, as 16 and 17, are journaled for free rotation upon the exposed end of the shaft, and the spiral development of the webs which constitute these worms is such as will describe right and left-hand threads, respectively. Each of the worms is encased in an annular sleeve, as 16' and 17', and these sleeves fit rather freely, the lower sleeve within the tube 7 and the upper sleeve within the tube 8, and by which it will be apparent that this latter tube is given a

shortened length by comparison with the outer tube 7.

The second said tube, internally considered, is of a relatively uniform diameter top to bottom, but upon its external surface presents a rather intricate system of grooves emanating toward the upper end, and which is to say at the lower limit of a solid collar 18 formed thereon, and carrying therefrom throughout the length of the body, the collar being of a length to terminate at or about the upper limit of the branch inlet openings.

I do not mean to imply that these grooves, and which constitute flow-channels governing, in part, the progress of the semifluid substances fed through the branch inlets into the machine, each run to the bottom end of the tube, but only that the tube is characterized by external grooving throughout that part of the tube which lies below a point coinciding with the upper limit of the branch openings. There are, in fact, two functionally independent systems of grooves—an upper and a lower system—and the system which lies uppermost handles approximately one-half the output of the supply branches 13, conducting this portion of the material to ports 19 which are cut through the wall of tube 8 and thus supplying same to the inside of the tube, while the other system is entirely isolated therefrom and receives from the supply branches the remainder of the introduced streams for conducting only this portion of the material along the outside of the tube to the bottom limit of the latter.

Describing said systems of grooves in more particularity, the upper system is in the nature of a belt-channel composed of four canals 20, V-shaped by preference, each extending through an approximate 90° compass and being separated one from another by a perpendicular partition 21. The placement of tube 8 within tube 7 is such as will locate these partitions on the vertical center line of the inlet openings, and semifluid streams from each of two adjacent branch inlets are hence introduced to each of the V-canals. Each of the canals feeds to a respective said port 19, with the latter located to register with the crotch of the V.

Relative to the lower system of grooves, there are described at the upper end of the system four rather wide channels separated one from another by webs 22 extending downwardly as perpendicular prolongations of the partitions 21. As will have been understood in course of the above description, and which can be best seen from an inspection of Fig. 1, the dividing wall between the upper and the lower system of grooves makes a juncture with the perpendicular divisions at points coinciding with the axial line of respective branch inlets. Two separate streams are thus fed into each of the V-canals, and also into each parent channel of the lower system of grooves, one being supplied from one division of one branch inlet and the other from one division of the next adjacent inlet.

Coursing downwardly along the outside of tube 8, the two streams accommodated by each parent channel are caused to converge toward a narrow throat produced by a flaring of the opposite side walls of each web 22, and leaving this throat are made to enter a series of diagonally directed and crossing canals described by a multiplicity of diamond-shaped blocks 23 which collectively gird the lower extremity of the tube. The blocks are arranged in several vertically spaced rows, staggered and lapped as respects the blocks in one and the blocks in the next adjacent row.

Proceeding now to describe the inner of the three tubes, namely the tube 9, the same extends to approximately the upper limit of the worm 17 without, however, contacting the latter and, internally considered, provides an unobstructed conduit arranged and adapted to make connection at the upper end with a supply line (not shown) separate and apart from the branch inlets 13. This supply line, where the machine is applied to ice cream, operates, preferably, to deliver a fruit mix held at an approximate 50° F. temperature and pressure fed at, say, 55# to 80#.

Exteriorly considered, there is provided at the head end of tube 9 a solid collar 24 extending to approximately the upper limit of the ports 19, the body therebelow being generally of a reduced diameter. Below a tapering shoulder and at or about the mid-height of this reduced body there is welded or otherwise rigidly secured upon the external surface a severality of spirally developed fins 25 projecting outwardly a distance—radially speaking—sufficient to find touching, or approximate touching, engagement with the inner wall of the surrounding tube 8. These fins are each given a bridging form leaving central openings, as 26, which in each instance occupy positions such that lines projected perpendicularly through these openings are interrupted above and below the fin in question by the solid ends of the next adjacent fins. Lying in spaced relation below the said fins and likewise made integral with the tube 9 are a multiplicity of rib elements 27 each extending perpendicular to the machine's axis and producing that which, sectionally considered, gives much the effect of a honeycomb with the cells thereby formed being quite restricted. The material issuing as thin strips from the lower end of these cells feeds directly into the openings described between the convolute webs of the upper worm 17, being joined therein by the fruit or other suitable substance issuing from the conduit formed internally of the tube 9.

The operation will have been largely apparent from the foregoing. The entering streams fed through the branch inlets 13 are divided, in the instance of each branch, into four streams which thereupon follow separate courses, two of these divisions working in opposite directions through separated V-canals of the upper system of the middle tube's external channels and being each joined by another and differently colored minor division of a major stream as the same feed through a related port 19 into the inner of the two treatment zones, namely the zone described between the tubes 8 and 9. The other two of the four minor divisions of each said major stream will, perchance, have been likewise joined by a differently colored minor division as the same follow separate courses travelling along the lower system of grooves to the labyrinth-like diagonal passages described between the multiple blocks 23. It becomes unnecessary to trace the exact manner in which these joined minor divisions are caused to be brought together, one with another of two joined minor divisions, and again separated, successively, and suffice it to say that a blending of the colors takes place to cause a "veining" of the streams as they issue from said outer treatment zone and are fed into the lower worm 16. Coincident with this treatment, the several divisions of the major streams which have been fed through the ports 19 will have been momentarily merged, then divided by the forced

travel through the interstices between the fins 25, and these divisions further divided as the same pass through and emerge from the through-cells produced by the ribbing 27, perforce deriving a similar "veining" in course of the transition from relatively thick to thin strips. These several strips, wrapped with the fruit mix, likewise traverse the convolutions of the lower worm 16 and are there brought into association with the "veined" issue of the outer treatment zone, working with the latter to the delivery end of the machine.

It has been my finding, in respect of ice cream, that a change of but a few degrees in temperature will very materially modify the marbleizing results, and the machine is hence quite flexible insofar as results are concerned. The temperature should not, however, drop below 22° F. nor rise above 28° F., for best results.

Numerous departures from the illustrated and described embodiment will suggest themselves to those versed in the art and may be resorted to without sacrifice of the inventive concept. I intend that all forms of construction and variation in detail coming within the scope of the hereto annexed claims are to be considered as comprehended by the invention.

What I claim is:

1. As a method of working a severalty of differently colored streams of semifluid matter into a marbleized pattern, and which comprises, working the streams under pressure through a confined treatment zone and, in course of travel, separating each parent stream into minor divisions, isolating these minor divisions of a common parent one from another and while so isolated joining each minor division of one with a minor stream of another and differently colored parent stream, dividing these joined streams of minor divisions into lesser strips, spirally wrapping a severalty of these strips, and compacting and discharging the several rope-like products of this wrapping step.

2. As a method of working a severalty of differently colored streams of semifluid matter into a marbleized pattern, and which comprises, working the streams under pressure through a confined treatment zone and, in course of travel, separating each parent stream into minor divisions, isolating these minor divisions of a common parent one from another and while so isolated bringing the minor divisions of differently colored parent streams into contiguity, again dividing, spirally wrapping a severalty of the divisions together, and compacting and discharging the rope-like products of this wrapping step.

3. As a method of working a severalty of differently colored streams of semifluid matter into a marbleized pattern, and which comprises, working the streams under pressure through a confined treatment zone and, in course of travel, guidably directing the streams along established individual paths which repeatedly merge only at separated intervals of the length, and collecting, compacting, and continuously discharging the matter as it emerges from these established paths of travel.

4. Given separate and confined treatment zones one in surrounding relation to the other, the method of compounding a severalty of differently colored streams of semifluid matter into a marbleized mass, and which comprises, supplying the streams separately and under pressure to the treatment zones and, before introduction thereto, dividing each of the parent streams into minor divisions, joining a minor division of one with a minor division of another parent stream, joining other minor divisions of said separate parent streams, causing one stream composed of these joined minor divisions to work progressively through the outer treatment zone and another stream composed of said joined minor divisions to work progressively through the inner treatment zone, concurrently, and in course of said travel reducing the streams to lesser strips, spirally wrapping the strips from both of said treatment zones together as they emerge therefrom, and continuously discharging the rope-like product of this wrapping step.

5. The method of claim 4, including the step of pressure-injecting a semifluid stream of a separate substance into the collection of strips emerging from the inner treatment zone and from a point central to the latter.

CONRAD C. A. REETZ.
